[57] **CLAIM**

The ornamental design for a cassette tape eraser, substantially as shown and described.

DESCRIPTION

FIG. 1 is a view in perspective of a cassette tape eraser showing our new design as seen from the top, one end and one side;

FIG. 2 is a side elevational view thereof showing the side opposite that seen in FIG. 1;

FIG. 3 is a view in top plan thereof;

FIG. 4 is an end elevational view thereof as seen from right to left of FIG. 2; and

FIG. 5 is an end elevational view thereof as seen from left to right of FIG. 2.

The bottom not shown is substantially plain.
